UNITED STATES PATENT OFFICE.

BENJAMIN F. ENNIS, OF SYRACUSE, NEW YORK.

SEPARATOR FOR COLLATED ARTICLES.

No. 876,627.

Specification of Letters Patent.

Patented Jan. 14, 1908.

Application filed May 20, 1907. Serial No. 374,679.

To all whom it may concern:

Be it known that I, BENJAMIN F. ENNIS, of Syracuse, in the county of Onondaga, in the State of New York, have invented new

5 and useful Improvements in Separators for Collated Articles, of which the following, taken in connection with the accompanying drawings, is a full, clear, and exact description.

10 This invention relates to certain improvements in separators for collated articles and contemplates the separation and feeding of any predetermined number of promiscuously collected units at regular predetermined 15 intervals, such for instance, as the separation and depositing of a predetermined number of seeds at regular intervals or distances apart in the ground.

15 The generic object of my present invention 20 is to separate the seeds or other articles or units by means of a rotary inclined hopper and one or more selectors or conveyers carried by the hopper in which said articles are placed promiscuously, by hand or otherwise.

25 In other words, I have sought to associate the selectors with the hopper in such manner that the seeds or other articles will automatically gravitate into the selectors and be carried thereby in predetermined quantities or 30 numbers upwardly from the bulk of the seeds or other articles and deposited in such predetermined quantities into a chute or passage leading from the hopper.

35 A further object is to provide means synchronized with the movement of the hopper and its selectors for recollecting and discharging predetermined quantities or numbers of such articles in the ground, or to any other locality, according to the nature of the articles which it is desired to separate and distribute.

40 Other objects and uses relating to the construction and operation of the various parts of the device will be brought out in the following description.

45 In the drawings—Figure 1 is a side elevation of a portion of a seed-planter embodying the various features of my invention. Fig. 2 is a sectional view taken on line 2—2, 50 Fig. 1, showing particularly the front end of the hopper and its actuating means, and also showing the selector-actuating devices. Fig. 3 is an enlarged vertical sectional view through the hopper and adjacent portion of 55 the supporting frame, showing also the actuating means for the hopper, and auxiliary

feed. Fig. 4 is a sectional view taken on line 4—4, Fig. 3. Fig. 5 is an enlarged sectional view taken on line 5—5, Fig. 1.

In carrying out the objects stated, a cylindrical hopper —1— is provided with a bottom —2— disposed in an inclined plane and having a central hub —3— which is journaled upon a fixed tubular bearing —4— forming a part of a supporting frame —5—.

60 As previously stated, the bottom of the hopper is disposed in an inclined plane, or rather, is inclined from a vertical plane, while the sides of the hopper are preferably cylindrical and form with the bottom, a hollow drum into which the seeds or other articles are placed promiscuously by hand, or otherwise, through an opening —6— in what 65 may be termed, the rear of the hopper.

As previously stated, the bottom of the hopper or drum —1— with a 70 series of, in this instance, six rocking 75 selectors or angular plates —7— are journaled at —8— in the bottom of the hopper or drum close to the circular sides thereof, and are movable into and out of engagement with fixed companion plates —9—, 80 which are also angular, and secured to the bottom of the hopper to form a series of, in this instance six, separate compartments or pockets —10—. In other words, I have provided the hopper or drum —1— with a 85 series of, in this instance six, pockets spaced equidistant apart close to the bottom —2— of which the circular sides of the drum form the outer walls and each pocket is provided with a movable gate or section 90 —7— hinged at —8— to the bottom —2—. These pockets are open toward the mouth or rear side of the hopper to permit the entrance of the seeds, or other articles to be separated, by gravity during the rotation of 95 the hopper; that is, the open sides of the pockets face rearwardly and upwardly while the bottom of the hopper forms the bottoms of the pockets.

The inner sides of each pocket nearest the 100 axis of rotation of the hopper is spaced apart some distance from the shell —1— to permit the entrance and retention of a number of seeds or articles to be separated and distributed, the ends of said pockets being deflected or offset laterally or outwardly 105 against the inner face of the shell —1— to prevent circumferential displacement of said seeds or articles while being carried upwardly by the pocket.

110 The movable section, as —7—, of each pocket which is journaled close to the shell

—1— is movable into and out of engagement with the inner face of the adjacent end of the fixed section —9— and is of such capacity as to receive and retain a single 5 one of the seeds or articles to be separated and constitutes the rear end of the pocket, or that opposite to the direction of rotation of the hopper. These movable gate-sections —7— are adapted to be closed against 10 the fixed sections —9— while traveling around the low side of the hopper and remain in this closed position until they are carried up to, approximately the highest point of the hopper, where they are caused 15 to be tilted to discharge the seed or other article which may be carried upwardly thereby from the bottom of said hopper. In order to accomplish this movement each gate —7— is rigidly secured to a spindle 20 —8—, which is journaled in a suitable aperture or bearing in the bottom —2— of the hopper and is provided at its front or lower side with a pawl 12—, weighted at —13—, and provided with an arm 14—, which engages, 25 or rather, rides upon a concentric substantially semi-circular track —15— at the bottom or lower side of the hopper for positively holding the movable gates —7— in their closed position against the fixed section 30 —9— of the pockets —10— while traveling around the low side of the hopper, the weights 13— performing a similar function, while the filled pockets are traveling upward to the top of the hopper.

35 It sometimes happens that a seed or other article to be separated is caught between the movable section —7— and fixed section —9— and carried in this position upwardly and in order that it may be released before 40 reaching the extreme upper side of the hopper, I provide one or more fixed agitator stops —11—, which in this instance, are secured to part of the supporting frame —5— and project into the path of the pawls 45 —12— so as to open the gate slightly— enough to release the seed or article thus caught, but not sufficient to permit the discharge of the articles from the pocket, or such article as may be held within the gate 50 —7—. A second fixed tripping finger —16— is secured to the frame near the top of the hopper and in the path of the pawls —12—, said stop finger being nearer the swinging axis of the gate —7— than the fingers 11— 55 so as to completely open the gate —7— and permit the discharge of the seed or article held thereby into an underlying fixed chute —17— which is rigidly secured to the fixed tubular bearing —4— of the frame —5—, 60 said chute extending upwardly and radially from the inner or upper end of the tube —4— into proximity to the plane of travel of the pockets —10—, the upper end of the chute —17— being open and being of sufficient circumferential length to assure the

reception of the seeds and other articles as they are discharged by the opening of the movable gates —7—.

It is now clear that the hopper 1 is provided with a series of pockets traveling in an inclined plane, each pocket receiving a limited number of seeds or other articles to be separated which are fed thereinto by gravity at the bottom of the hopper and are conveyed upwardly to a point directly over the open end of the chute 17 into which a predetermined number of seeds or other articles are deposited or discharged by the automatic opening of the movable gate —7— as soon as the corresponding pocket is brought directly over the chute, the movable gates being held closed through the medium of the pawls —12— riding on the track —15— aided by the weights 13— until they reach a point directly over the mouth of the chute —17—, 85 whereupon such gates are positively and automatically opened by the engagement of the pawls 12— with the tripping finger or arm —16—, as best seen in Figs. 2 and 3.

The hopper —1—, together with the parts carried thereby may be rotated by any suitable means, but in this instance, is driven from the main shaft —21— of the traction wheel —22— through the medium of gears —24—, a shaft —25— and spur gears —26—, 95 one of the gears —26— being secured to the hub —3— of the drum or hopper —1—.

As a further means for supporting and feeding the seeds or other articles in predetermined quantities or numbers, I provide a second chute or hollow tubular guide —23— which in this instance, is disposed in a vertical position and communicates with the inclined tubular guide —4— leading from the bottom of the chute —17— so that the seeds 100 or other articles which are deposited into the chute —17— fall by gravity along the bottom of the guide —4— and into the upright chute or delivery tube —23—, which, when used as a seed planter terminates at its lower 105 end in proximity to the surface of the ground and is provided near its lower end with a bottom —28— having an opening —29— therein to permit the discharge of the seeds 110 from the delivery tube upon the ground.

A vertical shaft —30— is journaled centrally within the delivery tube in a suitable bearing —31— at the upper end of the tube above the inclined chute —4—, and this shaft is provided with one or more vanes or 115 fins —32—, also extending from the point above the bottom of the chute —4— into proximity to the bottom of the delivery tube, the edges of said vanes or fins traveling in close proximity to the inner surface of the delivery tube —23— to sweep or brush the seeds which may accumulate on the bottom —28— into the opening —29— from whence they fall onto the surface of the ground, or into a suitable furrow previously made by a 120 125 130

plow-point —35— on the frame of the machine. This shaft —30— may be rotated by any suitable means, here shown as consisting of bevel gears —36— secured respectively to 5 the upper end of the shaft —30— and to the hub —3— of the drum —1— so that rotation of the shaft —30— is synchronized with that of the hopper.

In this particular instance, I have shown 10 the hopper and gates therein as adapted to successively discharge one seed at a time into the chute —17— whereby a number of, in this instance six, seeds or other articles are selected and discharged into the chute —17— 15 from whence they are precipitated by gravity along the bottom of the inclined chute —4— into the delivery tube —23—.

It is now clear that by properly proportioning the gears —24— and —26— the 20 drum or hopper —1— may be rotated any number of revolutions or fraction thereof at each revolution or fraction of such revolution of the traction wheel —22— and in this instance, I have shown the gears —24— as 25 of equal size, while the gears —26— are proportioned to rotate the drum or hopper —1— one-half revolution at each revolution of the traction wheel —22— thereby discharging a plurality of, in this instance three, seeds or 30 other articles at each complete revolution of the traction wheel —22—, the periphery of which may be of any desired length, as for instance three feet, whereby a series of three seeds may be deposited upon the ground in 35 hills three feet apart. It is evident, however, that many other mechanisms may be employed for discharging the seeds at regular intervals or in hills, and while I have shown and described a specific mechanism, 40 I do not limit myself thereto. In like manner the gears —36— may be proportioned so as to rotate the shaft —30— any predetermined number of revolutions or fraction thereof during each revolution of the hopper —1—, but as shown in the drawings, 45 these gears —36— are arranged to rotate the shaft —30— one-half revolution at each half revolution of the hopper so as to discharge a predetermined number of, in this 50 instance three, seeds which have been deposited upon the bottom of the delivery tube through the discharge opening —29—. This action of the shaft —30— may be either intermittent or continuous and I have 55 shown it continuous for the reason that ample time is given for the discharge of the seeds along the incline —4— into the delivery tube —23— between each revolution of the shaft, the seeds being deposited into 60 the side of the delivery tube nearest the chute —4—, at which side the bottom —28— is closed, the seeds falling upon such bottom and are immediately or subsequently scraped or brushed laterally by the blades —32— 65 into the discharge opening —30—, whence

the seeds fall upon the ground. This discharge of the seeds may be further regulated by means of a gate —40— movable across the discharge opening —29— and having an opening therein adapted to be brought 70 into registration with said discharge opening, said gate being in this instance, actuated at regular intervals by means of a lever —41— and an actuating member —42— on the shaft —25—, said gate being opened at 75 each revolution of the shaft —25— and traction wheel —22—, or at each half revolution of the drum —1— so as to permit the discharge of three seeds at each operation, or rather, at each revolution of the traction 80 wheel —22—. Any other suitable mechanism may be employed to vary the time of action of the gate —40— so as to deposit a greater or less number of seeds for a given distance of travel of the machine over the 85 surface of the ground, and therefore, I do not wish to limit myself to the exact device herein shown and described.

The operation of my invention will now be readily understood upon reference to the 90 foregoing description and the accompanying drawing, which are in such clear and exact terms as to enable anyone skilled in the art to make and use the same.

What I claim is:

1. In a separator for collated articles, a rotary hopper containing the collated articles and provided with an open pocket receiving a limited number of said articles, said pocket having a movable gate and 100 means to open said gate at regular intervals in the rotation of the hopper for discharging a predetermined number of said articles from the pocket, and means to receive said discharged articles to conduct them away from 105 the hopper.

2. In a separator for collated articles, a rotary inclined hopper having a series of pockets traveling in an inclined plane, each pocket having a portion of one side movable, and means for actuating said movable side during the rotation of the hopper.

3. In a separator for collated articles, a rotary hopper and actuating means therefor, a series of movable gates in the hopper each 115 adapted to receive and retain a predetermined number of said articles during a part of one revolution of the hopper, and means for opening said gate to discharge said articles during the rotation of the hopper.

4. A separator for collated articles comprising a revoluble drum and actuating means therefor, said drum having its bottom disposed in an inclined plane, a series of rocking gates journaled in said bottom in 120 close proximity thereto, and means for rocking said gates during the rotation of the drum.

5. A separator for collated articles comprising a rotary hopper having its axis dis- 130

posed in an inclined plane and adapted to contain the collated articles, a fixed chute within the drum and a series of movable selectors mounted in the drum each selecting and conveying a predetermined number of said articles from the bottom of the drum to a position over the mouth of the chute, and means for operating said selectors to discharge the articles therefrom as they are successively brought to a position over the mouth of the chute, whereby said articles fall into said chute.

6. A separator for collated articles comprising a fixed chute, and a rotary hopper 15 containing the articles to be separated and disposed in an inclined plane, said hopper having a series of movable selectors each conveying a limited number of articles from the bottom to the top of the hopper, means 20 for rotating the hopper and additional means for actuating the selectors to discharge the articles therefrom as they are successively brought to a position over the mouth of the chute, whereby said articles fall into the chute.

7. A separator for collated articles comprising a rotary hopper revolving about an inclined axis and provided with an axial opening, a chute within the hopper and communicating with said opening and a series 30 of movable selectors revolving with the hopper, each selecting a predetermined number of seeds and conveying them upwardly over the mouth of the chute, means for 35 rotating the hopper, and additional means for operating said selectors to discharge the articles therefrom as they are successively brought into registration with the mouth of the chute.

40 8. A separator for collated articles comprising a rotary hopper rotating about an inclined axis and adapted to contain a quantity of articles to be collated, means to rotate said hopper, a chute extending axially 45 through the center of the bottom of the hopper and provided with a radial offset located within the hopper and open at its outer end, a movable selector within and rotating within the hopper to and from a position over 50 the open end of the offset of the chute for supporting and conveying a predetermined number of said articles into registration with the open end of said offset, and means for operating said selector to discharge the article 55 therefrom into the opening of the offset of the chute when brought into registration therewith.

9. A separator for collated articles comprising a hopper rotatable about an inclined 60 axis and provided with an axial opening, a movable selector within and rotating with the hopper to select and convey a predeter-

mined number of said articles from the bottom to the top of the hopper, means for rotating the hopper, and additional means 65 for operating the selector when it is brought to the top of the hopper to discharge the article therefrom, and further means for receiving said discharged article and conducting it to the opening in the center of the 70 hopper.

10. A separator for collated articles comprising a fixed tubular bearing constituting a guide, a chute communicating with said bearing and open at the top, a hopper revolving about said bearing and chute and adapted to contain the collated articles, means for 75 rotating said hopper, a series of gates revolving with the hopper and adapted to receive and convey a limited predetermined 80 number of said articles from the collation over the mouth of said chute, and means for opening said gate when registered with the mouth of the chute to discharge the article from said gate into said chute.

85 11. A separator for collated articles comprising a fixed tubular bearing constituting a guide, a chute communicating with said bearing and open at the top, a hopper revolving about said bearing and chute and adapted to contain the collated articles, means for 90 rotating said hopper, a series of gates revolving with the hopper and adapted to receive and convey a limited predetermined number of said articles from the collation 95 over the mouth of said chute, and means for opening said gate when registered with the mouth of the chute to discharge the article from said gate into said chute, a delivery tube having a bottom provided with an opening in one side, and movable means in the tube for forcing the articles discharged thereinto into registration with said opening.

100 12. A separator comprising a delivery tube and an inclined chute communicating therewith, an upright chute communicating with the inclined chute, a hopper inclosing the upright chute, means to rotate the hopper and a series of movable gates rotating with the hopper and each adapted to receive 105 and convey a predetermined number of said articles from the collation within the hopper into registration with the mouth of the upright chute, and further means for opening 110 said gates as they are successively brought into registration with the mouth of said upright chute whereby the articles fall by gravity thereinto.

In witness whereof I have hereunto set my hand this 10th day of May 1907.

BENJAMIN F. ENNIS.
